UNITED STATES PATENT OFFICE.

NISBET LATTA, OF MILWAUKEE, WISCONSIN, ASSIGNOR, BY MESNE ASSIGNMENTS, TO
ALLIS-CHALMERS MANUFACTURING COMPANY, A CORPORATION OF DELAWARE.

GAS-PRODUCER.

1,142,524.

Specification of Letters Patent. Patented June 8, 1915.

Application filed May 16, 1910. Serial No. 561,655.

To all whom it may concern:

Be it known that I, NISBET LATTA, a citizen of the United States, residing at Milwaukee, in the county of Milwaukee and 5 State of Wisconsin, have invented a certain new and useful Improvement in Gas-Producers, of which the following is a specification.

This invention relates to improvements in 10 the construction of gas producers, and particularly to improvements in the construction of producers in which crude petroleum or other liquid hydrocarbon is utilized as a gas generating medium.

15 An object of the invention is to provide a gas producer utilizing a liquid hydrocarbon generating fuel, which is simple in its construction and efficient in operation.

A further object of the invention is to 20 provide a gas producer which can be directly connected to the suction of a gas engine or other gas utilizing apparatus, without necessitating the use of intermediate storage tanks or similar means to insure a 25 uniform supply of gas.

A clear conception of one embodiment of the invention can be obtained by referring to the accompanying drawing in which like reference characters designate the same or 30 similar parts in like or different views.

Figure 1 is a central vertical section of an oil gas producer built in accordance with the invention. Fig. 2 is a horizontal, transverse section of the device shown in Fig. 1, 25 the section being taken along the line II-II of Fig. 1, looking in the direction of the arrow. Fig. 3 is a horizontal, transverse section of the device shown in Fig. 1, the section being taken along the line III-III 40 of Fig. 1, looking in the direction of the arrow.

The gas producer consists essentially of a cylindrical brick shell 11 having vaporizing plates or inclined walls 1, 4, supported 45 therein. The upper end of the shell 11 is provided with an inclosing head formed of an incombustible material such as fire brick. The manhole 9 is formed in the center of the inclosing head and is provided with a cover 50 which is adapted to be removed to permit inspection of the interior of the shell 11. The lower end of the shell 11 is provided with a water seal 15, in the construction shown, but this is not essential, as a false 55 bottom constructed of fire brick or other

non-combustible material would be sufficiently effective. The water seal 15 is provided with a filling passage through which the water supply in the seal chamber can be replenished.

60 The inclined vaporizing wall 1 is lined with a suitable non-combustible material and extends downwardly and inwardly from a point near the top of and adjacent the shell 11 to about the center of the shell 11. 65 The chamber 2 is formed in the upper portion of the shell 11 adjacent the inclined wall 1. As shown, the surface of the inclined wall 1 which is exposed to the chamber 2, is a plane, the surface at the bottom 70 of the inclined wall 1 being curved to form an arch.

The oil inlet pipe 10 penetrates the producer walls near the top of the inclined wall 1 and is directed downwardly against the 75 surface of the inclined wall 1. There may be a number of these pipes 10 instead of one as shown, in order to obtain better distribution of the oil over the inclined wall 1. The pipe 10 may also be furnished with a distributing nozzle, thus producing the same effect produced by the use of a plurality of pipes as above described. The chamber 7 which communicates directly with the chamber 2, has a diaphragm 21 adapted to be 80 distorted by the absence or reduction of pressure within the chamber 7. The valve rod 20, which connects the valve 19 in the pipe 10 with the diaphragm 21, is either raised or lowered by the distortion of the diaphragm 90 21, thereby either closing or opening the valve 19. The valve 19 may be of any desirable type, a butterfly valve 19 being shown in the drawing, see Fig. 1.

The outlet pipe 6 directly connects the 95 chamber 2 with the gas utilizing apparatus, not shown, which may be a gas engine or other suitable apparatus adapted to utilize a continuous supply of gas. Poke holes 12 are formed in the shell 11 near the inclined 100 wall 1, and serve as a means for inspection of the surface of the inclined wall 1, these holes also serving as observation apertures, see Figs. 1 and 2.

The inclined wall 4 is lined with a suitable non-combustible and non-metallic material and extends downwardly and inwardly from a point opposite the central portion of the inclined wall 1 and adjacent the shell 11 to within a short distance from 105 110

the bottom of the shell 11. The chamber 5 is formed below the arch surface of the inclined wall 1 and between the inclined wall 4 and shell 11. This chamber 5 communicates with the chamber 2 through the restricted passage 3 formed between the two inclined walls 1, 4. The surface of the inclined wall 4 which is exposed to the chambers 2, 5, is a plane, the lower end of the inclined wall 4 being curved to form an arch. 5 A checker-work 16 of brick or other material forming a grate or hearth, is constructed near the lower end of the inclined wall 4, and has a plurality of ports or passages therethrough which connect the chamber below the inclined wall 4 and adjacent the water seal 15, with the chamber 5. A cleaning hole 13 is provided just above the checker-work 16 and serves as a means for 10 removing incombustible residue which may be precipitated upon the surface of the hearth or checker-work 16. Poke holes 12 are also provided and serve as means for inspecting the chamber 5. The air inlet 14, 15 having the controlling valve 17 therein, enters the chamber below the inclined wall 4 and above the water seal 15, being directed toward the vertical wall of the hearth or brick checker-work 16. 20 In placing the producer into operation, a small amount of highly combustible material, such as a piece of waste saturated with oil, is placed upon the upper surface of the hearth or brick checker-work 16 where it is 25 ignited. The valve 17 in the air supply pipe 14 is then opened and air is admitted into the combustion chamber 5 through the ports formed in the checker-work 16, causing the flame of the burning waste to rise into the 30 gasifying chamber 2. Oil or other liquid hydrocarbon is then permitted to enter the chamber 2 through the pipe 10, being precipitated upon the inclined wall 1 and there ignited by the flame from the burning waste. 35 Due to admission of a very large quantity of air into the producer during starting, the first liquid hydrocarbon or oil admitted is completely consumed, thus generating an intense heat. The heat generated is utilized 40 in bringing the surfaces of the inclined walls 1, 4, up to incandescence or gasifying temperature, thus establishing a heat zone within the producer. When the temperature of the lower portion of inclined wall 4 has 45 reached that of incandescence or gasification, the producer is ready for continuous operation and the air supply admitted through the inlet pipe 14 is reduced so that only a portion of the oil is consumed, the 50 quantity of air admitted depending upon the quality of gas desired. The oil admitted through the pipe 10, in passing over the highly heated plate or inclined wall 1, has its volatile matter distilled during its downward passage, the various fractions thereof

being broken up at their appropriate temperatures. The residual of solids or semi-solids other than volatile matter, continues to pass down over the inclined wall 1 and from there onto the inclined wall 4, until it is finally completely consumed in the chamber 5 due to its continual intermingling and contact with the air supply. The heat resulting from this combustion produces a continual supply of heat required to maintain the plates or inclined walls 1, 4, at the gasifying temperature. 70 75

The products of combustion of the residual matter, which products are drawn upwardly through the volatilized hydrocarbons by the reduced pressure or suction in the outlet 6 are more or less carbureted and mingle or mix with the effluent gases incident upon the preliminary distillation. The mixture is withdrawn from the outlet 6 after 80 a short period of fixing in the upper end of the shell 11 to be utilized as desired. The withdrawal of the fixed gas from the gasifying chamber 2 may be accomplished directly by the suction of a gas engine, by a fan or 85 exhauster, or any other suitable means of producing a suction or reduction of pressure in the outlet 6. The amount of air induced through the producer is proportionate with the gas or fuel demand by the engine, fan or 90 exhauster, or, with the pressure of the gas in the outlet 6, and may be regulated automatically by the flow of gas in the outlet 6 acting on the inlet valve 17. 95

The regulation of the supply of liquid hydrocarbon or oil through the pipe 10 is effected by the diaphragm 21, valve rod 20 and valve 19. The suction or reduction of pressure in the outlet 6 acts through the chambers 2, 7, onto the diaphragm 21 causing said diaphragm to be distorted and lower the rod 20 or open the valve 19. This opening of the valve 19 increases the supply of liquid hydrocarbon fuel proportionately to the demand for gas or to the reduction of 100 pressure in the outlet 6. It will therefore be seen that the elements—heat, oil and air—the former being the result of the combustion of the oil in the presence of air, are approximately proportional and coördinate in 105 their regulation, their admission being dependent upon and synchronizing with the demand upon the producer by the engine, fan or exhauster, or with the reduction of pressure in the outlet 6. 110

By using the brick hearth or checker-work 16, two results are accomplished; first, the air entering the chamber 5 is prevented from columning, being broken up into a spray as it emerges from the hearth; and second, the 115 entering air is preheated in passing between the hot bricks of the checker-work 16, being admitted to the chamber 5 at a reasonably high temperature. The bricks of the checker-work 16 are heated by the combustion of the 120 125 130

solid matter above them and also by refraction of the heat resulting from said combustion, from the lower arch surface of the inclined wall 1 and from the side of the shell.

5 The water seal 15 at the bottom of the producer serves the purpose of preventing injury to the shell 11 in event of back-firing in the producer. This water seal may also enrich the finally resulting gas produced by 10 adding thereto a slight amount of hydrogen which is evaporated and rises to the gasifying chamber 2 in the form of steam.

The use of brick or similar non-metallic substance for lining the surface of the inclined walls 1, 4, and the shell 11, prevents 15 so-called over-cracking, crocking, drying, or over-burning of the oil as well as preventing shock, crystallization and precipitation of the carbon element through over-rapidity or 20 suddenness in the disbursement of the hydrogen element. If metal distilling inclined walls 1, 4, were used, the disbursement of the hydrogen elements would be quickened, due to the refracting and heat reflecting powers 25 of the metallic substances and the increased co-efficiency of heat transference between metallic substances and oils or vapors in excess of that afforded by non-metallic materials, such as brick or stone.

30 The use of a long cylindrical shell 11 with inclined walls 1, 4, arranged therein as shown and described, causes the hydrocarbon contained in the fuel to be broken up and fixed by direct contact and by radiation, the 35 length of shell 11 and resulting distance traveled by the gases before leaving same, giving ample opportunity for complete fixing of the gas before leaving the producer. The reverberatory effect within the producer 40 tends to conserve the heat within the shell 11 to reduce radiation to adjacent elements, and to permanently fix the hydrocarbons of the gas within the producer. The plurality of plates or inclined walls 1, 4, are not intended 45 to serve as distributing plates or baffles for the liquid hydrocarbon fuel, these inclined walls 1, 4, serving as distilling

plates or heat retainers, as heretofore explained. The inclined walls 1, 4, fractionally distil or crack the oil at certain critical 50 temperatures, each fraction of the oil being cracked or distilled at an appropriate temperature, thus preventing overcracking, burning or precipitation of the hydrocarbon matter through an excess of heat and producing more delicate hydrocarbon combinations or gases. 55

It should be understood that it is not desired to be limited to the exact details of construction shown and described, for obvious modifications will occur to a person skilled in the art. 60

It is claimed and desired to secure by Letters Patent,—

1. In a gas producer, an elongated shell, 65 a plurality of inclined vaporizing walls within said shell, a liquid fuel inlet above one of said inclined walls, an air inlet below another of said inclined walls, said inlets being adapted to feed fuel and air respectively continuously toward the interior of said shell and said inclined walls gravitating material from the one to the other, a gas outlet adjacent said fuel inlet, and pressure actuated means for controlling the fuel to 70 assist in maintaining proportionality between the amounts of fuel and air admitted through said inlets. 75

2. In a gas producer, a shell, a plurality of vertically spaced vaporizing walls within 80 and inclined relatively to said shell, a liquid fuel inlet adjacent the upper end of one of said walls, said inlet constituting the sole ingress for fuel to said shell, an air inlet below the lower of said walls, positive means 85 for preventing eolumning of the air admitted, and a gas outlet at the upper end of said shell.

In testimony whereof, I affix my signature in the presence of two witnesses.
